UNITED STATES PATENT OFFICE.

GEORGES EVENO, OF PARIS, FRANCE.

LUBRICATING PADDLE FOR JOURNAL BOXES.

Application filed July 17, 1924, Serial No. 726,633, and in France July 20, 1923.

The present invention relates to lubricating devices for bearings and more particularly to an oil distributing and elevating device or paddle used in connection with journal boxes of railroad cars wherein the oil is raised automatically during the travel of the railroad car and properly distributed over the bearings and axle arranged within the journal box.

10 The purpose of the present invention is to render more perfect the lubrication of journals or axles of railroad cars by providing an oil elevating paddle which will not beat the oil as it passes through the oil well of the journal box, but will merely cut through the oil and elevate the same to the bearing of the journal box whereby a constant supply of oil will be fed thereto and permitted to be evenly distributed thereover.

20 It is likewise an equally important object of the present invention to provide in connection with journal boxes of railroad cars a novel, simple and efficient oil elevating paddle having opposed oil collecting pockets therein whereby the oil may be collected by the paddle and distributed over the bearing.

Other objects of the invention will be in part obvious and in part pointed out hereinafter.

30 In order that the invention and its mode of operation may be readily understood by those skilled in the art, I have in the accompanying illustrative drawings and in the detailed following description based thereupon, set out one possible embodiment of the invention.

In these drawings:

40 Figure 1 is a vertical longitudinal section through an ordinary journal box having the invention as applied thereto,

45 Figure 2 is an enlarged longitudinal section through the elevating paddle, and

Figure 3 is an enlarged detail in perspective of the improved oil elevating paddle.

50 Referring now more particularly to the accompanying drawings wherein like and corresponding parts are designated by similar reference characters throughout the several views, the numeral 1 indicates a journal box adapted to receive the axle 2 of the railroad car and this journal box having the usual oil well 3 formed therein. Arranged between the journal box and the axle is the usual brass 4 having a projecting end 4' which latter projects over the outer end of the axle 2. In order to elevate and carry

the oil from the well 3 of the journal box to the brass or bearing block 4 whereby it may be distributed thereover, disks, paddle wheels and the like have been heretofore provided which are carried by and secured to the outer end of the axle 2 so that upon the rotation of the axle the disk will elevate the oil above the bearing block 4 and deposit the same thereupon. If the axle 2 is revolving very fast, disks as heretofore used will cause the oil to be deposited upon the bearing block 4 but as the axles do not at all times rotate at a very high speed these disks will not elevate the oil unless there is provided suitable means for collecting the oil upon the disk. Therefore, by the present invention I have devised an oil elevating device or paddle wherein the oil will at all times be collected during the rotation thereof and deposited upon the bearing block 4.

The oil elevating device or paddle embodying the present invention is preferably of strap metal having a hub portion 5 provided with suitable means through which a fastening member 6 may extend for securing this elevating paddle to the outer end of the axle 2. The several faces of the paddle are so formed as to provide opposed pockets 7 and 8 and these pockets having points of greatest depth upon the opposite sides of its perpendicular axis which latter is indicated by the broken line A-B as illustrated in Figure 2 of the drawing. These pockets as it will be evident from Figure 2 of the drawing do not extend to the outer edges 9 of the paddle whereby a plain outer edge will be provided which will cut through the oil contained within the well 3 of the journal box and will not beat the oil or stir the same as it passes therethrough. Formed within the paddle are a plurality of openings 10 which provide the means of a communication between the oil collecting pockets 7 and 8 as well as permitting a portion of the oil contained within the pockets 8 to flow to the bearing block 4 during the rotation of the journal to which the paddle is attached.

From Figure 1 of the drawing it is obvious that when the paddle embodying the present invention is applied to the end of an axle 2 the projecting end 4' of the bearing block extends within the pocket 7 so that upon the rotation of the paddle the oil contained within this pocket 7 will be caused to flow upon and below the projection 4' so

that it may be evenly distributed over the bearing block. It will also be further noted that the oil collecting within the pocket 8 will be permitted to drain through the openings 10 onto the upper face of the projecting ledge 4.

I claim:

1. A lubricating paddle for journal boxes comprising a metal strap, a hub portion 10 formed therewith adapted to be connected to the journal so as to rotate therewith, the several faces of said paddle being formed with opposed pockets adapted to collect the oil within the journal box during the rotation thereof, said pockets having points of 15 greatest depth upon the opposite sides of the perpendicular axis of the paddle, said

pockets having outlet openings at one side of the paddle whereby the oil contained within the pockets may flow upon the bearing of the journal box during the rotation thereof and blades formed with the outer ends of said strap.

2. A lubricating device formed from a single strip of metal shaped to provide an 25 attaching portion and pockets on opposite sides of said portion, certain of said pockets discharging directly on the axle and the remaining discharging through openings in the strip.

In testimony whereof I have signed my name to this specification.

GEORGES EVENO.
